FIG. 3.

C. M. PUTNAM—INVENTOR.

BY *Beale & Park*
ATTORNEYS.

UNITED STATES PATENT OFFICE.

CHARLES MARSH PUTNAM, OF ALMA, MICHIGAN.

CORN STRINGER.

1,416,752.

Specification of Letters Patent. Patented May 23, 1922.

Application filed October 24, 1921. Serial No. 510,172.

To all whom it may concern:

Be it known that I, CHARLES MARSH PUTNAM, a citizen of the United States, residing at Alma, in the county of Gratiot and State of Michigan, have invented certain new and useful Improvements in Corn Stringers; and I hereby declare that the following is a full, clear, and exact description thereof, reference being had to the accompanying drawings, which form part of the specification.

My invention relates to improvements in corn stringers whereby I am able to string seed corn rapidly and without bruising same.

My device provides for weaving the corn between strings in such a manner that the strings are drawn taut but not tight enough to force their way between the grains or bruise them.

Referring to the drawings: Fig. 1 shows a vertical cross section of my corn stringer. Fig. 2 is a horizontal cross section on the line 2—2 of Fig. 1. Fig. 3 is an enlarged portion in cross section showing how the strings pass through the slides.

Referring more particularly to the drawings: 10 and 11 denote complementary sliding frames attached to each other by rope 12 which passes over pulley 13 which pulley is mounted on stationary frame 14; cross bars 15 are attached to this frame and slidably hold the sliding frames 10 and 11 in proper relation to said stationary frame 14. Sliding frame 10 is provided with horizontal bushings 16. Sliding frame 11 is provided with a screw eye 17 bent at right angles.

At the lower end of the sliding frame 10 is attached a weight 18 to counterbalance a treadle 19 attached by link 20 to the lower end of sliding frame 11. The treadle 19 swings upon hinge 20 $\frac{1}{2}$ attached to the supporting frame of table 21. A coil spring 22 is attached to the table 21 and the treadle 19 aiding in the quick return of the treadle to a normal position after being depressed in operation of my device.

The slanting table 21 is secured to the stationary frame 14 by cross bar 23 and slanting support 24. Slightly above and on the opposite side from the table 21 is tension table 25 secured to stationary frame 14 by means of braces 26. Upon the tension table 25 are mounted four metal spring

plates 27 which are bent so as to be held in hinged position by staples 28. A bolt 29 passes through the table 25 through a hole provided in plate 27 and is there surrounded by a coil spring 30 held in proper adjustable tension by wing nut 31. Plates 27 rest upon a flat metal bar 32. Attached by staples to the table 25 are guides 33, 34, 35 and 36. The guides are provided with a bent end which keeps them from slipping out from between the staples in which they are hinged and also limit the downward motion of the guide. The outer portion of these guides form a loop through which the rope or twine used in my device is threaded. The guides direct and also take up any slack in the twine.

In the operation of my device four balls of rope or twine denoted by 37 are placed upon the ground or floor, the ends of said twine being passed through holes 38 in tension table 25, thence over the flat metal bar 32 and under spring plate 27, thence the twine is threaded respectively through the guide 33, 34, 35 and 36. The twine passing through guides 33 and 36 is threaded through screw eyes 17 in the sliding frame 11. The twine passing through guides 34 and 35 is threaded through bushings 16 provided in sliding frame 10.

The table 21 is provided with guide rails 39. It will be noted that at the point 41 where the operator passes the ears of corn denoted by 40, between the cords 37, this rail 39 is omitted to allow the corn to be quickly slipped onto the table. After an ear of corn has been placed between the cords the treadle 19 is pressed downward by the foot of the operator this causes the sliding frame 11, to descend and its complementary sliding frame 10 to rise, thus carrying two cords up and two down, another ear of corn is then passed between the cords in their new position, the operator then releases the pressure of his foot and the complementary sliding frames resume their original positions assisted by weight 18 and spring 22.

This operation is repeated until the desired number of ears have been strung, the cords are cut and the strung ears are removed and placed to one side preparatory to removal to the drying house. The cut ends of the twine are again knotted and the process again repeated.

It will be seen from the above descrip-

tion that the number of ears strung per day is only limited by the speed at which the operator can feed the ears. The slant of the table 21 aids in sliding or pushing the 5 corn down the table when strung.

It will further be seen that the corn may be strung as tightly as desired by regulating the tension of springs 30 on the tension table together with the pushing pressure exerted by the operator in sliding the strung 10 corn down the slanting table 21.

It is apparent that my device provides for stringing the ears of corn with even tension and that the number of ears strung have 15 little or any effect upon this tension, the weight of the strung ears being supported upon my slanting table. The ears of seed corn are strung in parallel relation to each other there being no limit to the number 20 that may be strung in any one series.

It is also apparent from the construction and plainly shown in Fig. 1 that the slanting table 21 is slotted so as to permit the cords 37 to pass beneath the level of said 25 table on the down stroke of the sliding frames 10 and 11 respectively. This it will be seen permits the ears of corn to rest upon the surface of the said table and at the same time slide between the said cords.

30 Claims:

1. A corn stringer of the class described comprising an upstanding frame, complementary sliding frames mounted therein, a rope connecting said sliding frames, a 35 pulley for supporting said rope mounted in said upstanding frame, a tension table attached to said upstanding frame provided with tension spring plates, bolts and springs, a slanting table opposite said tension table 40 and attached to said upstanding frame,

strings threaded through said tension means and passed through said sliding frames in pairs respectively, a treadle hinged to said slanting table and attached to one of said sliding frames and a weight attached to the other sliding frame whereby the movement of said treadle will alter the relation of said sliding frames and said weight upon the release of said treadle will return said sliding frames to normal position crossing and recrossing said pairs of string thereby stringing ears of seed corn in parallel relation. 45 50

2. A corn stringer of the class described comprising an upstanding frame, complementary sliding frames mounted therein, a rope connecting said sliding frames, a pulley for supporting said rope mounted in said upstanding frame, a tension table attached to said upstanding frame provided with tension spring plates, bolts and springs, a slanting table provided with cord slots therein said table being located opposite said tension table and attached to said upstanding frame, strings threaded through said 60 tension means and passed through said sliding frames in pairs respectively, a treadle hinged to said slanting table and attached to one of said sliding frames and a weight attached to the other sliding frame whereby 65 the movement of said treadle will alter the relation of said sliding frames and said weight upon the release of said treadle will return said sliding frames to normal position crossing and recrossing said pairs of string 70 thereby stringing ears of seed corn in parallel relation. 75

In testimony that I claim the foregoing as my own, I affix my signature.

CHARLES MARSH PUTNAM.
